United States Patent Office

Des. 203,687
Patented Feb. 8, 1966

203,687

CLOCK

Andrew Weining, 1317 Lynn St., Erie, Pa.

Filed Apr. 7, 1964, Ser. No. 79,388

Term of patent 14 years

(Cl. D42—7)

The drawing is an isometric view of a clock embodying my new design.

The end which is not shown is similar to the end shown. The back is plain.

The front of the clock case is substantially flat with surface decoration thereon as shown.

I claim:

The ornamental design for a clock, as shown and described.
